UNITED STATES PATENT OFFICE.

EDWARD GURNEY, OF TORONTO, ONTARIO, CANADA.

DESIGN FOR A HOT-WATER HEATER.

SPECIFICATION forming part of Design No. 18,548, dated August 21, 1888.

Application filed June 23, 1888. Serial No. 278,050. Term of patent 14 years.

To all whom it may concern:

Be it known that I, EDWARD GURNEY, a subject of the Queen of Great Britain, residing at the city of Toronto, in the county of York, in 5 the Province of Ontario, Canada, have invented and produced a new and original Design for a Hot-Water Heater, of which the following is a specification, reference being had to the accompanying drawing, forming part thereof.

10 The drawing represents a perspective elevation of my newly-designed sectional hot-water heater.

The leading feature of my design consists of a stove or furnace having a series of circular 15 sections having curved projections, the outline of the said curved projections falling within the circular outline or circumference of the main body of the section, the said sections being provided with a bead formed on 20 the bottom side of each section and projecting over the section.

The drawing represents the side of the boiler on which the doors are located.

A represents the curved projections. The 25 outlines of these projections are curved so that they fall entirely within the circular outline or circumference of the circular center B.

C represents circular lugs formed on each section at the point where the curved lines of

the projections enter the curved lines of the 30 circular center B. The doors E and F are located as indicated.

The fuel-door G is located as shown, and has 35 vertical elongated holes and provided with a suitable damper. The ash-pan door H has vertical elongated openings provided with a suitable damper. The bead I is formed on the bottom of each section and projects over the edge of the section below. The top of the upper section is smaller in diameter and projects above 40 the outside of the section, an ogee sweep being formed.

I claim—

The design for a hot-water boiler herein 45 shown and described, the same consisting of a series of circular sections having curved projections, the outlines of the said curved projections falling within the circular outline or circumference of the main body of the section, the said sections being provided with a bead 50 formed on the bottom side of each section and projecting over the section below, curved lugs being formed on each section, as shown.

Toronto, June 13, 1888.

EDWARD GURNEY.

In presence of—

DONALD C. RIDOUT,
CHARLES C. BALDWIN.
